UNITED STATES PATENT OFFICE

JOHN GELOSO, OF NEW YORK, N. Y., ASSIGNOR, BY MESNE ASSIGNMENTS, TO PILOT RADIO & TUBE CORPORATION, OF BROOKLYN, NEW YORK, A CORPORATION OF DELAWARE

TUBE SOCKET

Application filed March 21, 1927. Serial No. 176,862.

This invention relates to improvements in cushion sockets, being particularly directed to sockets wherein the vacuum tube supported thereby may be positioned in a resiliently supported floating base.

One of the inherent difficulties encountered in present day radio receptions is introduced in the use of fixed sockets, due to the fact that the shocks imparted to the receiver are transmitted through the socket and the prongs, and the vacuum tube associated therewith, functioning elements within the tubes, whereby distortion is introduced in the tube through the amplification process therein.

It is with the viewpoint of eliminating this difficulty and similarly introducing a novel form of cushion socket involving a plurality of associated elements, one of which, comprising the carrier, is cushioned against shock due to the fact that it, the carrier, is suspended in a floating relationship with respect to the remainder of the elements, by means of a plurality of inter-acting flexible members.

Broadly then, it is an object of this invention to provide for a flexible socket member in which a floating member, carrying the prongs of a vacuum tube associated therewith, may be displaced in a vertical and horizontal plane, with the provision that upon the attainment of element in either of the above said planes, the flexible element will not of itself be overextended beyond its normal movement range; by means of a positive stop associated therewith.

Specifically, it is the aim of this invention to provide for a flexible socket in which movement of a carrier member composing one of the elements therein, may be limited in all planes, but which movement is sufficient to absorb any jars in the said planes which may be imparted to the vacuum tube, carried therein.

Further, it is an aim of this invention to provide for a socket member, which, being composed of three interengaging elements, may be readily assembled by any person, in which, due to its ease of assembling, may be applied, in all or in part, to a panel member within a radio circuit.

Still further, it is the aim of this invention to provide for a flexible stamped conductor member, which serves as a resilient spring for maintaining the head of the socket in floating relationship with respect to the base thereof, and which conductor member is adapted to carry a stop or carrier member, disposed at the intermediate portion thereof, and which conductor member is positively fixed at one end to the base member, and maintained in fixed position within chambers formed in the head member by pressure, due to its tendency to expand.

These and other advantages, capabilities, and features of the invention will appear from the subjoined detail description of one specific embodiment therefor illustrated in the accompanying drawings, in which,

Figure 1 is a plan view of the device.

Figure 2 is a side elevation of the device.

Figure 3 is a plan view looking upwardly towards Figure 2.

Figure 4 is a plan view of the conductor members.

Figure 5 is a side elevation partly in section of the structure shown in Figure 2.

Figure 6 is a side elevation, partly cut out, showing the head and carrier member.

Figure 7 is an end elevation in section, along lines 7—7 of Figure 6.

Figure 8 is a perspective view of the conductor member.

Figure 9 is a plan view of a modified form of the device.

Figure 10 is a side elevation of the structure shown in Figure 9.

Figure 11 is a plan view of a second modified form of the invention.

Figure 12 is a side elevation of the structure shown in Figure 11.

Figure 13 is a view in perspective of the conductor member used in the structure in Figures 11 and 12.

Referring to the reference characters in the drawing, numeral 20 represents an insulating base, to which the wiring terminals are adapted to be attached, the said base having an aperture 21 therein, within which aperture there is adapted to be positioned a conductor carrying member 22. This con-

ductor carrying member comprises an insulating member having lateral extending carrier portions 23, in which apertures 24 are formed for the passage therethrough, for a flexible conductor member 25, to be later described.

This carrier or stop member 22 has a series of arms or vanes 26 formed integral with, and extending perpendicularly and horizontally from, the lateral arms, which arms have projecting portions 27 extending beyond the periphery of the aperture 21 within the insulating base 20, so that the movement of the carrier member is limited by the said projections, which form a stop due to the contact of the portions 27 with the periphery 21.

A series of terminals 28 are positioned along the outer periphery of said base member 20, which terminals are adapted to carry the conductor members 29, comprising the usual bolt and nut for inter-connection of this device with the remaining portions of the circuit. A series of insulating blocks 30 are formed along the under portion of the insulating member 20, being integral therewith, and serving to support the same in position.

Extending centrally and upwardly from the carrier member 22, there is formed a hub member 31, which hub member has a nut 32 positioned interiorly thereof, the said nut being adapted to cooperate with a screw member 33, passing through the head 34. The upper portion of the hub member 31 has a projection 35, which cooperates with an aperture 36, and the hub 37, of the head member 34, so that the head and the supporting member may be directly associated with one another for operation within the base member.

The head member 34, as shown in Figures 6 and 7, comprises a molded insulated member, having a plurality of channels 38 therein, which channels terminate in one side in the form of a semi-circle as 39. This chamber 38, reaches to a point adjacent the top of the head member 34, and a circular opening 40 forms a continuation to the top of the head member. The screw member 33 is adapted to be positioned within the aperture 41, formed within the head member 34, and positioned so as to pass out of sight within the said aperture.

Referring to Figures 4 to 9 inclusive, the contact members 42 are adapted to be formed of a single sheet of stamped metal, slideable through and within the apertures 24, and are shaped so that the portion 43, resting and in contact with the supporting member 22, is narrow. The conductor member is bent so that the extremity 44 is adapted to form a resilient pressure contact with a noncircular portion 45, of the chamber 38, while the main portion 45 is adapted to be positioned cen-

trally of the aperture 40, adjacent the semi-circular portion 39 within the chamber, so that prongs extending downwardly from a vacuum tube, contact directly with the face 45 of the conductor.

The bent-over portion 46 is adapted to be positioned under the support member 22, after the conductor 42 has been positioned within the support, and the portion 46 drawn along and under the insulating base 20. The end extremity 47 of the conductor 42, is offset from the portion 46 thereof, so as to allow for added resiliency; the portion 47 being fixed to the insulating base 20 by means of a screw member 48.

Referring to Figures 9 and 10, a modification is shown wherein the socket base is formed by a panel member 50, to the underside of which there are adapted to be fixed respective leads 51, by means of bolt members 52. The panel member 50 has an aperture centrally disposed therein, which aperture is attachable to the carrier member 53, through which the contact members of the same type as shown in Figure 8 are adapted to be supported. The head member 54 is similar in structural detail to that shown in Figure 7.

Referring to Figures 11, 12, and 13, a modified form is shown wherein the cushioning effect is not provided for. In this type of structure a molded head 60 is attachable to the base 61 by means of the screw 62, to which the bolt 63, at the underpart of the base 61, is attachable. The conducting prongs 64 comprise a bent stamping, the head 65 of which is adapted to fit into the chamber of the same type as that shown in Figure 7 within the head member 34. The extremity 66 of said stamping extends perpendicularly from the base 61, as shown in Figure 13, is bent over in actual operation for fastening to the remaining elements in the circuit.

It is obvious that various changes and modifications may be made to the details of construction without departing from the general spirit of the invention as set forth in the appended claims.

What I claim is:

1. In a device of the class described, the combination with a supporting member, contact terminals on said supporting member, a head member having apertures therein for the passage of prongs therethrough, and flexible conductor members, having one extremity positioned within said head member, and the other extremity fastened to the contact terminals on said supporting member, said head member being thereby floatingly supported with respect to the supporting member, and means attachable to said head member, and through which said flexible conductor members pass, for limiting the movement of the head member with respect to the supporting member.

2. In a device of the class described, a base member, a head member cooperating therewith, chambers within said head member, conductor members fixed to said base member, and extending upwardly and inwardly and resting within the chambers in said head member, said conductor members being adapted to be locked within said head member by pressure contact whereby the head member may be supported in floating relationship with respect to the base member, and means comprising an insulating member attachable to said head member, and having apertures therein for the passage therethrough, and the retention of said conductor members, whereby to limit the floating movement of said head member.
